UNITED STATES PATENT OFFICE.

VICTOR E. RANDALL, OF BATTLE CREEK, MICHIGAN, ASSIGNOR OF ONE-HALF TO
BENJAMIN GWATKIN, OF BATTLE CREEK, MICHIGAN.

EMERGENCY TRAIN-STOPPING DEVICE.

1,286,407.

Specification of Letters Patent. Patented Dec. 3, 1918.

Application filed November 9, 1917. Serial No. 201,089.

To all whom it may concern:

Be it known that I, VICTOR E. RANDALL, a citizen of the United States, residing at Battle Creek, in the county of Calhoun and State of Michigan, have invented certain new and useful Improvements in Emergency Train-Stopping Devices, of which the following is a specification.

The present invention consists of a portable device to be attached to the rail joint-plates of a railroad for engaging apparatus on a train especially equipped so that in passing, the contact with said device will bring the train to a stop.

The principal object of the invention is to afford a mechanism of the character set forth that may be readily applied to the rail joint-plates in cases of emergency for the stopping of trains entering danger zones caused by breakdowns, wrecks or other mishaps incident to railway traffic.

An embodiment of the device is illustrated in the accompanying drawing in which Figure 1 is a side elevation of the device attached to the rail joint-plate.

Fig. 2 is an end elevation of the device attached to a rail joint.

Fig. 3 is a longitudinal sectional plan view of the device, the section showing the rail and its joint-plates bisected along their bolting line.

In the drawings, like marks of reference refer to corresponding parts throughout the different views, in which A, represents T-rails; B, the railway cross-ties; and C, the rail joint-plates, the joint plates being fitted to either side of the rails and the parts secured by means of bolts 1 in the customary manner.

Engaging the opposite ends of a joint-plate C on the outer side of the rail, the inwardly-hooked terminals 2 of the clamping members 3 and 4 are fitted and the members snugly drawn together by the provision of a rack and pinion, hereinafter more fully set forth, causing one member to slide upon the other.

As herein shown the member 3 is a sheath open at the end opposite its hooked extremity and on its outer side is formed with a slot 5 communicating with said open end, the slot affording a passageway through which the rack 6 of the sliding member 4 may extend.

The member 3 is formed with a side ex-

tending bracket 7, between the upper and lower sides of which a gear 8 adapted to mesh with the rack 6 is fitted, an upper extension 9 of said bracket forming an arm adapted to project in the path of and to actuate said train stopping mechanism when coming into contact therewith, and while I have shown a rigid arm for the purpose set forth, I reserve the right to employ an arm or device having an element of flexibility or other nature to meet the exigencies of mechanism on a train to be equipped with our train-stopping mechanism which engages said arm or device to stop said train.

The gear 8 is fitted to a short vertical shaft 10 journaled through the opposite sides of the bracket 7, and on its upper end carries a fixed gear 11 that meshes with a worm 12 fitted on a crank shaft 13, the worm being fitted between the arm 9 and a lug 14 extending from the bracket 7. The lug 14 and arm 9 are provided with well-aligned holes forming bearings within which the crank shaft 13 is journaled, a crank 15 being attached to said shaft by which the worm 12 may be operated to roll the gears 11 and 8 and cause the rack 6 and its hooked member 4 to slide within and on the member 3.

To prevent the clamping members from downward thrust or strain, a vertically-adjustable shoe 16 is fitted to the outer side of the bracket 7. This shoe standard is formed with a vertical adjusting slot 17 through which a bolt or stud 18 projects from the bracket 7, and on the threaded outer extremity of which a correspondingly-threaded hand adjusting wheel 19 is fitted, the arrangement of the parts being such that the shoe may be raised or lowered as occasion requires, and rigidly held when so adjusted.

Joint-plates, as C, are usually formed somewhat concave on the side adapted to engage a rail, and when bolted to place leave elongated narrow openings between the rail and the plate at the plate ends within which the hooked members of the clamping mechanism may be inserted, (a slot of this nature is represented in Fig. 2), the same providing a ready and exceedingly stable arrangement by which the portability of the emergency device is made practical and efficient.

From the foregoing description taken in

connection with drawing, a more extended explanation of the operation and advantages of the device is believed not to be necessary.

5 Having, therefore, described my invention, what I claim as new, and desire to secure by Letters Patent, is:—

1. In a device of the class set forth, the combination with the rails and the joint-plate connectively bolting them, of the hooked clamping members engaging the ends of said joint-plates between said joint-plates and said rails, the arm extending from said clamping members for engaging 15 train-stopping mechanism, and means for attaching or releasing said clamping members from said joint-plate, for the purpose set forth and described.

2. In a device of the class set forth, the
20 combination with the rails and the joint-
plate connectively bolting them, of the
hooked clamping members engaging the
ends of said plates between said plates and
said rails, the arm, extending from one of
25 said clamping members for engaging train
stopping mechanism, and means to, slidably
move said clamping members longitudinally
on one another, for the purpose set forth and
described.

30 3. In a device of the class set forth, the combination with the rails and the joint plates connectively attached thereto, of hooked members engaging the ends of said joint plates between said rails and said joint plates and longitudinally slidable on one another, means projecting from said joint plates for engaging train stopping mechanism, means to adjustably slide said hooked members in locked contact, and means to stabilize said hooked members, for the purpose set forth and described.

4. In a device of the class set forth, the combination with the rails and the joint-plate connectively bolting them, of the hooked members engaging the ends of said plates between said plates and said rails, the arm extending from one of said clamping members for engaging train stopping mechanism, means for slidably moving one of said members upon the other, and a stabilizing shoe adjustably fitted to said members, for the purpose set forth and described. 45 50

5. In a device of the class set forth, the combination of the slidably fitted hooked members, the bracket extending beyond one of said members, the spur gear journaled in said bracket, the rack of one of the said hooked members engaging said gear, the worm gear fitted to the shaft of said spur gear, the worm engaging said worm gear, the crank on the shaft of said worm gear, the arm extending from said bracket, and the vertically-adjustable shoe fitted to said bracket, substantially as set forth and described. 55 60 65 66

6. In a device of the class set forth, the combination with the rails and the joint plate connecting them, of longitudinally adjustable members having inwardly facing hooked outer extremities engaging the ends of said joint-plate between said joint plates and said rails, one of said members forming a sheath open at its inner end and open along its outer side, the other of said members fitting within said sheath, and means to longitudinally move one member with respect to the other in locked engagement. 70 75
